IMPROVEMENT IN OIL WELLS.

THOMAS M. FOSTER, OF UNION MILLS, PENNSYLVANIA.

Letters Patent No. 60,165, dated December 4, 1866.

SPECIFICATION.

TO ALL WHOM IT MAY CONCERN:

Be it known that I, THOMAS M. FOSTER, of Union Mills, in the county of Erie, and State of Pennsylvania, have invented a new and useful Improvement in Oil Wells; and I do hereby declare that the following is a full, clear, and exact description thereof, which will enable others skilled in the art to make and use the same, reference being had to the accompanying drawings forming part of this specification.

The present invention relates particularly to the sucker-rods, so called, used in oil wells, and its object is to preserve the tubing and economize expense. The sucker-rods first used were made of ordinary gas-pipe, but owing to their great length in proportion to their size, they soon became bent, and wearing the sides of the tubes were consequently abandoned, and wooden sucker-rods introduced, the latter being made in sections of suitable lengths, joined together with iron straps riveted to the wood. The great objection to the wooden rods, however, was, that as the wood became soaked with oil, which occurs very soon, the rivets used for securing its sections together, draw out and falling into the well render it necessary to withdraw the tubing to remove the rivets, which, as is well known, is an expensive and tedious operation, or otherwise they would injure the working-barrel of the pump; and moreover, the too frequent drawing of the tubing is inclined to injure the well. By my improvement embraced in the present invention all the advantages of a wooden sucker-rod are obtained without any of its objections, it consisting in making the sucker-rod of gas-pipe as hitherto, and in sections say each of fifteen feet in length or thereabouts, and put together with the ordinary sucker-rod joint, and a wooden collar of about ten and a half inches long, slipped over the rod at the joint; the said wooden collar being much larger than the rod, so as to prevent the rod from coming in contact with the tubing, but of the same size as the ordinary wooden sucker-rods, thus leaving the same space for the flow of oil in the tube.

In accompanying plate of drawings my improvement in sucker-rods is illustrated, the figure being a central section through the same taken in the direction of its length.

A, in the drawings, represents a portion of a sucker-rod, made of the ordinary gas-pipe, used therefor, and prepared to receive the wooden collar or sleeve, B; *a a* the ordinary and common gas-pipe couplings, joining the two sections of the sucker-rod marked A A², in the drawings, together through the connecting piece of pipe, D, over which and the couplings, *a a*, fits the collar B, herein before referred to, whereby it is firmly held in place. On each end of the wooden collar an iron ferrule, E, is secured.

I claim as new, and desire to secure by Letters Patent—

The sleeve B, sections A A, couplings *a a*, connecting piece D, and ferrule E, combined and operating substantially as described, as and for the purpose specified.

THOMAS M. FOSTER.
